UNITED STATES PATENT OFFICE.

JOSEPH TENNEL RYAN, OF MAYSVILLE, KENTUCKY.

CAN.

No. 829,086.

Specification of Letters Patent.

Patented Aug. 21, 1906.

Application filed August 24, 1905, Serial No. 275,576.

To all whom it may concern:

Be it known that I, JOSEPH TENNEL RYAN, a citizen of the United States, residing at Maysville, in the county of Mason and State of Kentucky, have invented certain new and useful Improvements in Cans; and I do declare the following to be a full, clear, and exact description of the invention, such as will enable others skilled in the art to which it applies to make and use the same.

My invention has relation to improvements in hermetically-sealed cans; and it consists in the construction and arrangement of parts, as will be hereinafter described, and particularly pointed out in the claim.

In the accompanying drawings, Figure 1 is a perspective view of a can constructed in accordance with my invention. Fig. 2 is a similar view of the same, showing the manner in which the cover or closure of the can is removed. Fig. 3 is a vertical sectional view through the can. Fig. 4 is a perspective view of the device for removing the contents of the can, and Fig. 5 is a perspective view of the key used for removing the cover or closure of the can.

Referring to the drawings by numeral, 1 denotes a can or similar container of any desired form and construction, but which is shown as of cylindrical form and of tin or other sheet metal. The can 1 has its top or cover 2 provided with a surrounding rim-flange 2', said cover being hermetically sealed thereon by soldering the annular rim or flange 3 of said cover, as shown at 4, said flange being constructed flaring, as shown at 4', to form a continuous channel between it and the body of the can to receive the solder. To permit the cover to be readily removed, its rim or flange 3 is scored or grooved in its outer face at two points 5 6. These grooves or scores extend entirely around the rim 3 and are preferably in parallel relation, as shown. At a suitable point in the rim is formed an angularly or diagonally disposed cut or slit 7, which forms a tapered tongue 8, which is adapted to be engaged by the opening-key 9. (Shown in Fig. 5.) The cut or slit 7 extends from the edge of the rim 3 to a point adjacent to the upper groove or score 5, and from the inner end of the cut or slit to said groove or score 5 is formed a short groove or score 10, as clearly shown in Fig. 1. The tongue 8 is preferably bent outwardly to a slight extent, so that it may be readily engaged by the key 9 and so that the solder or

other sealing material 4 may be poured beneath it to effectively seal the cover or closure. The opening-key 9 (shown in Fig. 5) may be of any form and construction; but I preferably make it of a piece of heavy wire or metal rod by bending one of its ends at right angles to form a crank or finger-piece 11 and bending its opposite end upon itself to form a slit or opening 12 to receive the tongue 8. In opening the can, as shown in Fig. 2, the tongue is inserted in the slit 12, and the key 9 is rotated to wind the flaring rim 4', the lower bead 6, and the strip 3 upon it as said rim is ripped along its score or groove 5 and the solder 4. The groove or score 6, it will be seen, is disposed a sufficient distance above the soldered edge of the rim 3 so that should the solder hold too effectively that portion of the rim between its edge and the score or groove 6 will tear, and the cutting will be along the groove or score 6, as well as the groove or score 5. These grooves or scores 5 6 are so formed that the portion of the rim between them will readily tear or strip off as it is wound upon the key. The short score or groove 10 causes the slit 7 to readily run into the upper groove or score 5 when the can is being opened.

In order to permit the contents of the can to be readily taken out after its cover has been removed, I provide a follower 15, which is in the form of a disk of slightly less diameter than that of the can 1. This disk is adapted to lie upon the bottom of the can, and projecting upwardly through the latter from the center of said disk is a rod 16, which has at its upper end an eye or loop 17, which forms a finger-piece. The rod 16 is approximately as long as the depth of the can, so that the loop or eye 17 lies directly beneath the cover 2 in position to be readily grasped when the latter is removed from the can. The lower end of the rod 16 may be secured to the disk or follower 15 in any desired manner; but I preferably pass the same through a centrally-disposed aperture in said disk or follower and bend said end at right angles and solder it to the bottom of the disk, as shown at 18. It will be seen that after the cover 2 is removed from the can the contents of the latter may be readily removed by pulling upwardly upon the rod 16. In practice I preferably fill the can through its bottom, which latter is soldered on after the disk or follower 15 has been placed in its position in the can.

From the foregoing description, taken in

connection with the accompanying drawings, the construction, operation, and advantages of the invention will be readily understood without requiring a more extended explanation.

Various changes in the form, proportion, and the minor details of construction may be resorted to without departing from the principle or sacrificing any of the advantages of this invention.

Having thus described my invention, what I claim as new, and desire to secure by Letters Patent, is—

The combination with a can-body, a cover therefor having a wide depending flange soldered to the body, a removable strip located in the flange and bounded by two parallel score-lines, a flaring rim on the lower edge of

the flange and below the lower score-line, whereby a channel is formed between the can-body and the lower edge of the flange so as to facilitate soldering, an oblique slit in the lower edge of the flange and a score in alignment with such slit and extending from the upper end of said slit to the upper parallel score-line thus forming a starting-tongue which is adapted to be engaged with a key for the removal of the strip.

In testimony whereof I have hereunto set my hand in presence of two subscribing witnesses.

JOSEPH TENNEL RYAN.
